(57) **CLAIM**

The ornamental design of a desk, as shown and described in the drawings and specification.

DESCRIPTION

FIG. 1 is an isometric top front view of a desk, showing my new design.

FIG. 2 is an isometric bottom front view thereof.

FIG. 3 is a front view thereof.

FIG. 4 is a rear view thereof.

FIG. 5 is a left view thereof.

FIG. 6 is a right view thereof.

FIG. 7 is a bottom view thereof; and,

FIG. 8 is a top view thereof.

The broken line portion of the figure drawings is included to show portions of the article that forms no part of the claimed design.

1 Claim, 5 Drawing Sheets
